SWITCH LOCK CONTROL
AND INDICATION

William H. Claus, Downers Grove, Ill., assignor to
The Union Switch and Signal Company, Swiss-
vale, Pa., a corporation of Pennsylvania

Application June 13, 1947, Serial No. 754,337

10 Claims. (Cl. 246—219)

1

My invention relates to switch lock control and indication, and particularly to remote manual control of a switch lock and take-siding indicator for a railway track switch, and to control of indication means at a remote point according to the position and the locked or unlocked condition of the switch.

In order to prevent operation of a railway track switch away from its normal position except under the direction of a dispatcher or leverman, it is common practice to provide an auxiliary lock lever at the switch for locking the switch in its normal position, and to provide an electric lock which, if deenergized while the lock lever is in its normal position, locks the lever in that position. Energization of the electric lock for releasing the lock lever is effected by a dispatcher or leverman. A trainman can then unlock the switch by moving the auxiliary lock lever to its reverse position, after which he can move the switch to its reverse position.

One feature of my invention is the provision of a novel and improved arrangement for controlling an electric switch lock and a take-siding indicator for a switch, and for indicating to the dispatcher or leverman, after he has released the electric lock, that the lock lever is still in the normal position, and also for indicating when the lock lever is moved away from the normal position, and again when the lock lever and the switch have been restored to their normal positions.

A further feature of my invention is the provision of means for effecting all these controls and indications over only two line conductors.

I shall describe one form of apparatus embodying my invention, and shall then point out the novel features thereof in claims.

The accompanying drawing is a diagrammatic view showing one form of apparatus embodying my invention, in which an electric lock for locking a railway track switch in its normal position, and a take-siding indicator for directing traffic movements over the switch in its reverse position, are controlled from a remote point over a given pair of line conductors, and in which three indications are controlled by the lock lever and the switch over the same pair of line conductors.

Similar reference characters refer to similar parts in the drawing.

In the drawing, contacts operated by the various relays or other devices are identified by numbers, such numbers having distinguishing prefixes from which they are separated by a dash

2

when the contacts are shown apart from the relay by which they are operated. The prefix for each of these contact numbers comprises the reference character for the respective relay by which the contact is operated. For example, contact LR—20 shown adjacent the symbol for relay NS is identified by the number 20 separated by a dash from the prefix LR which is the reference character for relay LR by which this contact is operated.

Referring further to the drawing, rails 4 and 4a of a stretch of railway track are divided by insulated joints 5 to form a section 3T which includes a switch 3. Section 3T is provided with a track circuit including a suitable source of current, such as a battery 6, connected across the rails adjacent one end of the section, and a track relay, designated by the reference character 3TR, connected across the rails adjacent the opposite end of the section. Adjacent the left-hand end of section 3T, as shown in the drawing, a track relay, designated by the reference character 4TR, of a track circuit for another section is shown.

25 A signal designated by the reference character 1S governs traffic movements toward the right, as shown in the drawing, which I shall assume is the eastbound direction, over section 3T. A second signal designated by the reference character 2S governs traffic movements in the opposite or westbound direction over section 3T. Signals 1S and 2S may be of any suitable design, such for example as the well-known searchlight type.

35 A take-siding indicator designated by the reference character SK, shown as a lamp, is normally dark but, upon becoming lighted, directs traffic movements from section 3T over switch 3 in the reverse position to a siding Z.

40 Switch 3 may be operated between its extreme positions by any suitable mechanism not shown in the drawing. A lock bar 7 is rigidly secured to switch 3 for engagement with a dog 8 by means of which switch 3 is locked in its 45 normal position in which it is shown in the drawing. Dog 8 is actuated by a manually operable lock lever designated by the reference character 2V having a normal position *n* and a reverse position *r*.

50 Lever 2V is locked in its normal position *n* by an electric lock L comprising a control winding *d* and an armature having a dog 9 for engagement with a notch 10 of a locking segment *f* which is rigidly connected with lever 2V. Lever 2V operates a contact 11 which is closed when lever 2V

is in the normal position and becomes opened when lever 2V is moved away from the normal position.

A contact 12 is operated in conjunction with switch 3 and is closed when switch 3 is in its normal position but becomes opened when switch 3 is moved away from its normal position.

A switch repeater relay, designated by the reference character 3P, is controlled by contacts 11 and 12 of lever 2V and switch 3, respectively.

Energization of lock winding d is controlled by a control relay LR. Relay LR and a code following indication relay CF are connected in series with each other and with the back point of a contact 27 of a code delivery relay CD in a line control circuit. This line control circuit is controlled by a contact 25 of a control lever 1V which has a normal position n and a reverse position r. Contact 25 and another contact 41 also operated by lever 1V are open when lever 1V is in its normal position n, but become closed when lever 1V is moved to its reverse position r.

A take-siding indicator control relay SKR is also controlled by relay LR and by an indication stick relay NS. Take-siding indicator SK is controlled by relay SKR and by relay 1TR, so that indicator SK is lighted only when a train is approaching signal 1S while relay LR is energized.

A slow release track repeater relay 3TP is controlled by a front contact of relay 3TR.

Indication stick relay NS is controlled by relays 3P, 3TR, 3TP and LR.

A code transmitting device designated by the reference character 75CT closes its front contact at a frequency of 75 times per minute, and is controlled by relays LR, NS and 3P. A second code transmitting device designated by the reference character 180CT, which closes its front contact at a frequency of 180 times per minute, is controlled by the same relays which control device 75CT.

A code delivery relay CD is controlled by code transmitting devices 75CT and 180CT, and by the three relays which control the code transmitting devices.

Only a portion of the circuit by which signal 1S is controlled to display the proceed indication is shown, and this portion is controlled by relays 3TR, 3P and LR. Likewise, only a portion of the circuit which controls signal 2S to display the proceed indication is shown, and this portion includes contacts of relays 3P and 3TR.

When energization of relay CD is being controlled by coding device 75CT, contact 27 of relay CD closes at its front point and opens at its back point at a frequency of 75 times per minute. When energization of relay CD is controlled by coding device 180CT, contact 27 of relay CD closes at its front point and opens at its back point at a frequency of 180 times per minute. Each time that contact 27 becomes closed at its front point, it completes a closed circuit path including the windings of relay LR, which prevents relay LR from releasing its front contacts during periods when the line control circuit is open at the back point of contact 27 of relay CD.

Indications relay CF controls decoding apparatus comprising a decoding transformer M, a resonant unit 180DU, and decoding relays 3PR and 3PN. When relay CF is being periodically energized at a frequency of 75 or 180 times per minute, its contact 42 repeatedly reverses the direct current applied to a primary winding m of transformer M so that alternating current is produced in secondary winding y of this transformer. The alternating current thus produced in second-

ary winding y is rectified by contact 47 of relay CF for energizing relay 3PN. Relay 3PN is therefore energized whenever relay CF is being operated at either the 75 or the 180 frequency. Resonant unit 180DU, however, permits relay 3PR to respond to only current of the 180 frequency.

When relay CD is deenergized while contact 25 of lever 1V is closed, so that contact 27 of relay CD is constantly closed at its back point, relay CD is constantly energized, and therefore constant direct current is supplied to primary winding m of transformer M. Relays 3PN and 3PR are therefore deenergized.

Relays CF, 3PN and 3PR control indication means shown as indication lamps G, W and A.

Lever 1V, relay CF, the decoding apparatus, and the indication lamps may be located at any suitable remote point, such as a dispatcher's office or an interlocking tower.

Having described, in general, the arrangement of the various parts of apparatus embodying my invention, I shall now describe the circuits and operation in detail.

As shown in the drawing, all parts of the apparatus are in the normal condition, that is, switch 3 is in its normal position; signals 1S and 2S are displaying a proceed indication; take-siding indicator SK is unlighted; the track sections shown in the drawing are unoccupied, so that track relays 1TR and 3TR are energized; levers 1V and 2V are in their normal or n position; relays 3P, 3TP and NS are energized; lock winding d, relays CF, LR, SKR, CD, 3PN, 3PR, coding devices 75CT and 180CT, transformer M, and indication lamps G, W and A are deenergized.

The portion of the control circuit shown in the drawing for signal 1S passes through contact 13 of relay 3TR, contact 14 of relay 3P, contact 15 of relay LR, and the mechanism of signal 1S to terminal N of a suitable source of current. The portion of the control circuit shown for signal 2S includes contact 16 of relay 3P and contact 17 of relay 3TR.

The circuit by which relay 3P is energized passes from terminal B of a suitable source of current, not shown in the drawing, through contact 11 of lever 2V closed in the n position, contact 12 of switch 3, and winding of relay 3P to terminal N of the same source of current.

Relay 3TP is energized by a circuit passing from terminal B, through contact 18 of relay 3TR, and the winding of relay 3TP to terminal N.

Both a pick-up and a stick circuit are closed for energizing relay NS, the pick-up circuit passing from terminal B, through the front point of contact 3P-19, contact LR-20, winding of relay NS, and the front point of contact 3P-24 to terminal N. The stick circuit which is closed for this relay passes from terminal B, through the front point of contact 3P-19, front point of contact 21 of relay 3TR, front point of contact 22 of relay 3TP, contact 23 of relay NS, winding of relay NS, and the front point of contact 3P-24 to terminal N.

I shall assume that, with apparatus arranged as shown in the drawing, it is decided that an east-bound train is to move from section 3T over switch 3 in its reverse position to siding Z. A dispatcher or leverman will therefore move lever 1V to its r position, thereby closing contact 25 in a line control circuit which passes from terminal B, through contact 25 of lever 1V, winding of relay CF, line conductor 26, back point of contact 27 of relay CD, and the winding of relay LR to terminal N.

Relay LR, upon becoming energized by this

circuit, opens its contact 15, thereby causing signal 1S to indicate stop. Relay LR, upon closing its front contacts, completes a circuit for energizing lock winding *d*, this circuit passing from terminal B, through contact 28 of relay LR, and winding *d*, to terminal N. At the same time, relay SKR becomes energized by a circuit passing from terminal B, through contact 28 of relay LR, contact 29 of relay NS, and the winding of relay SKR to terminal N.

The pick-up circuit traced for relay NS is now opened at contact LR-20, but relay NS remains energized by its stick circuit previously traced. Contact 36 of relay NS therefore remains open, and so relay CD remains deenergized.

Relay CF is therefore constantly energized, and lamp W is lighted by a circuit passing from terminal EB of a suitable source of lighting current, back point of contact 30 of relay 3PN, contact 31 of relay CF, and lamp W to terminal EN of the same source of lighting current.

When a train arrives on section 1T, causing relay 1TR to become deenergized, take-siding indicator lamp SK becomes lighted by a circuit passing from terminal EB, through contact 33 of relay SKR, contact 34 of relay 1TR, and indicator SK to terminal EN.

I shall assume further that a trainman goes ahead, and reverses lever 2V before the east-bound train enters section 3T. Contact 11 of lever 2V is thereby opened and causes relay 3P to become deenergized. When relay 3P becomes deenergized, its contact 16, in the circuit for signal 2S, becomes opened.

Contacts 3P-19 and 3P-24 momentarily open the stick circuit for relay NS and then reverse the polarity of current applied to this stick circuit causing contact 23 of relay NS to open. With the pick-up circuit for relay NS already open, and the stick circuit thus opened, relay NS remains deenergized.

A circuit is therefore completed for energizing code transmitting device 180CT, this circuit passing from terminal B, through contact 35 of relay LR, contact 36 of relay NS, back point of contact 37 of relay 3P, and the winding of code transmitting device 180CT to terminal N. Code delivery relay CD is therefore now periodically energized, at the frequency of 180 times per minute, by a circuit passing from terminal B, through contact 35 of relay LR, contact 36 of relay NS, back point of contact 38 of relay 3P, contact 40 of code transmitter 180CT, and the winding of relay CD to terminal N.

As previously pointed out, relay LR retains its front contacts closed while contact 27 of relay CD is repeatedly closing alternately at its front and back points. The contacts of relay CF, however, open at their front points and close at their back points each time that contact 21 opens at its back point.

With contact 42 of relay CF being repeatedly closed alternately at its front and back points, direct current is repeatedly supplied alternately in opposite directions to primary winding *m* of transformer M. Alternating current is therefore generated in secondary winding *y* of transformer M, and therefore relay 3PN is energized by current which is rectified through the front and back points of contact 41 of relay CF in a well-known manner. Since relay CF is being operated at a frequency of 180 times per minute, relay 3PR is also energized from terminals 44 and 45 of transformer M through resonant unit 180DU.

With relays 3PN and 3PR both energized, lamp

A is lighted by a circuit passing from terminal EB, through the front point of contact 30 of relay 3PN, front point of contact 32 of relay 3PR, and lamp A to terminal EN.

- 5 I shall now assume that all parts of the apparatus are again in the normal condition as previously described, and that a leverman then reverses lever 1V and another train enters section 1T, causing lock winding *d* and relay SKR to be energized as before, and take-siding indicator SK to be lighted, as previously described. As previously pointed out, relay NS is now energized by its stick circuit after relay LR has become energized. If, now, the train enters section 3T 10 before a trainman reverses lever 2V, relay 3TR will become deenergized, and hence its contact 21 will open the stick circuit for relay NS.
- 15 When relay 3TR becomes deenergized, its contact 17, in the circuit for signal 2S, becomes opened.

20 Relay 3TP also will now become deenergized because contact 18 of relay 3TR is open, but relay 3TP is of the slow releasing type, and therefore its contact 22 does not at once open at the front point and close at the back point. During the interval between the closing of contact 21 of relay 3TR at its back point and the closing of contact 22 of relay 3TP at its back point, relay NS is deenergized and its contact 23 opens. Since contact LR-20 in the pick-up circuit of relay NS is open, relay NS will then remain deenergized.

25 Since the trainman has not yet reversed lever 2V, relay 3P is still energized, and therefore a circuit is now completed for energizing code transmitting device 180CT, this circuit passing from terminal B, through contact 35 of relay LR, contact 36 of relay NS, front point of contact 37 of relay 3P, and code transmitting device 180CT to terminal N. Relay CD is therefore now periodically energized at a frequency of 75 times per minute by a circuit passing from terminal B, through contact 35 of relay LR, contact 36 of relay NS, front point of contact 38 of relay 3P, contact 39 of code transmitter 180CT, and the 30 winding of relay CD to terminal N.

35 With relay CF now energized periodically at a frequency of 75 times per minute, relay 3PN is energized as previously described, but relay 3PR will not become energized because of the resonant unit 180DU, which prevents response of relay 3PR to any but the frequency of 180 cycles per minute.

40 Lamp G is therefore now lighted by a circuit passing from terminal EB, through the front 45 point of contact 30 of relay 3PN, back point of contact 32 of relay 3PR, and lamp G to terminal EN.

45 If, now, a trainman reverses lever 2V, relay 3P will become deenergized as previously described, causing code transmitter 180CT to become energized and cause delivery relay CD to become energized at the frequency of 180 times per minute. Relays 3PN and 3PR will therefore both be energized, causing lamp A to be lighted as previously 50 described.

55 With lever 2V reversed, dog 8 will be withdrawn from lock bar 7, and therefore the trainman can now reverse switch 3 for the train to move from section 3T to track Z. Contact 12 of switch 3 60 will therefore be opened in the circuit for relay 3P which is, however, already deenergized on account of contact 11 of lever 2V being open.

65 When a trainman returns switch 3 to its normal position, relay 3P will still be deenergized until 70 lever 2V is returned to its normal position, thereby 75

closing contact 11. Code transmitter 180CT will therefore remain energized and lamp A will continue lighted until both switch 3 and lever 2V have been returned to their normal positions.

When lever 2V and switch 3 have both been returned to their normal positions, relay 3P will become energized by its circuit previously traced. Code transmitter 75CT will then be energized by its circuit previously traced, causing lamp G to again become lighted as previously described.

The dispatcher or leverman will then return lever 1V to the normal position, thereby deenergizing relays CF and LR, lock winding d, relay SKR, and relay CD. With relay LR now deenergized and with relay 3P again energized, relay NS will become energized by its pick-up circuit previously traced, and will then close its stick circuit also previously traced. With relay CF deenergized, decoding relays 3PN and 3PR will be deenergized, and lamps G, W and A will be dark.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a control and indication arrangement for an electric lock for a lock lever which locks a railway track switch in its normal position and with which a take-siding indicator is associated which directs traffic movements over said switch in the reverse position, the combination comprising, a manually operable control lever having a normal and a reverse position, a code following relay, a control relay, a code delivery relay, a line control circuit including a reverse contact of said lever and the control element of said code following relay and also a back contact of said code delivery relay and the winding of said control relay all in series with each other and energized by a suitable source of current, means controlled by said control relay in its energized condition for energizing said electric lock for releasing said lock lever and for preparing a circuit for energizing said take-siding indicator, means controlled by said control relay and by said lock lever for energizing said code delivery relay by coded current, and means controlled by said code following relay when said line control circuit becomes closed for displaying a given indication until said lock lever is moved away from its normal position and for then displaying a second indication while said lock lever is reversed and for displaying a third indication when said switch is again locked by said lock lever in its normal position.

2. In a control and indication arrangement for an electric lock for a lock lever which locks a railway track switch in its normal position and with which a take-siding indicator is associated which directs traffic movements over said switch in the reverse position, the combination comprising, a manually operable device, a code following relay, a control relay, a line control circuit controllable by said manually operable device for energizing said control relay in series with said code following relay, means controlled by said control relay in its energized condition for energizing said electric lock for releasing said lock lever and for closing a contact in a control circuit for said take-siding indicator, means controlled by said control relay in the energized condition and by said lock lever upon being moved away

from its normal position for periodically interrupting said line control circuit at a given frequency, means controlled by said control relay in the energized condition and by said switch and said lock lever upon being returned to their normal positions for periodically interrupting said line control circuit at a given different frequency, and indication means controlled by said code following relay.

3. In a control and indication arrangement for an electric lock for a lock lever which locks a railway track switch in its normal position and with which a take-siding indicator is associated which directs traffic movements over said switch in the reverse position, the combination comprising, a code following relay, a control relay, a manually controllable line circuit for energizing said code following relay and said control relay in series, means controlled by said control relay in its energized condition for energizing said electric lock and for closing a contact in a control circuit for said take-siding indicator, means controlled by said control relay in the energized condition and by said lock lever for periodically interrupting said line circuit at a given frequency when said lock lever is moved away from its normal position and for periodically interrupting said line circuit at a given different frequency when said lock lever is returned to its normal position, and indication means controlled by said code following relay.

4. In a control and indication arrangement for an electric lock for a lock lever which in its normal position locks a railway track switch in its normal position, the combination comprising, manually controllable means for energizing said electric lock for releasing said lock lever, and indication means controlled by said manually controllable means for displaying a given indication while said lock lever remains in its normal position after said electric lock becomes energized and for then displaying a second indication when said lock lever is moved away from its normal position and also for displaying a third indication by an aspect which is different from the aspect of said indication means for displaying either said first or said second indication when said lock lever is returned to its normal position.

5. In a control and indication arrangement for an electric lock for a lock lever which in its normal position locks a railway track switch in its normal position, the combination comprising, a control relay, an indication relay, manually controllable means for at times constantly energizing said control and indication relays in series, a circuit controlled by a front contact of said control relay for energizing said electric lock for releasing said lock lever, means controlled by said lock lever upon then being moved away from its normal position for periodically deenergizing said indication relay but preventing said control relay from releasing its front contacts, means controlled by said lock lever upon being returned to its normal position for again periodically deenergizing said indication relay, and indication means controlled by said indication relay.

6. In a control and indication arrangement for an electric lock for a lock lever which in its normal position locks a railway track switch in its normal position, the combination comprising, a control relay, an indication relay, manually controllable means for at times energizing said control relay for releasing said electric lock, a lever repeater relay controlled by a normal contact of said lock lever, a coding device con-

trolled by a front contact of said control relay and by a back contact of said lever repeater relay, a second coding device controlled by a front contact of said control relay and by a front contact of said lever repeater relay, means controlled by said first and second coding devices for controlling said indication relay, and indication means controlled by said indication relay.

7. In a control and indication arrangement for an electric lock for a lock lever which in its normal position locks a railway track switch in its normal position, the combination comprising a control relay for controlling said electric lock, a code following relay, a manually controllable contact, a coding contact, a line control circuit including said control and indication relays and said coding contact and also said manually controllable contact all in series with each other and energized by a suitable source of current, a lever repeater relay, a control circuit for said lever repeater relay including a normal contact of said lever, a stick relay, a pick-up and a stick circuit for said stick relay each controlled by pole-changing contacts of said lever repeater relay and said pick-up circuit also controlled by a back contact of said control relay, means controlled by a front contact of said control relay and by a back contact of said stick relay and by front and back contacts of said lever repeater relay for controlling said coding contact, and indication means controlled by said indication relay.

8. In a control and indication arrangement for an electric lock for a lock lever which in its normal position locks a railway track switch in its normal position, the combination comprising, a control relay for controlling said electric lock, a code following indication relay, a manually controllable contact, a coding contact, a line control circuit including said control and indication relays and said coding contact and also said manually controllable contact all in series with each other and energized by a suitable source of current, a lever repeater relay, a control circuit for said lever repeater relay including a normal contact of said lever, a track circuit for a section of track in which said switch is located including a source of current and a track relay, a track repeater relay controlled by a front contact of said track relay, a stick relay, a pick-up and a stick circuit for said stick relay each controlled by pole-changing contacts of said lever repeater relay and said pick-up circuit also controlled by a back contact of said control relay and said stick circuit also controlled by a front contact of said track relay in series with a front contact of said track repeater relay together with a

branch path around these front contacts including back contacts of the same two relays, means controlled by said control relay and by said lever repeater relay and also by said stick relay for controlling said coding contact, and indication means controlled by said indication relay.

9. In a control and indication arrangement for an electric lock for a lock lever which in its normal position locks a railway track switch in its normal position, the combination comprising, manually controllable means controlled over a given pair of conductors for energizing said electric lock for releasing said lock lever, and indication means controlled over the same pair of conductors for displaying a given indication while said lock lever remains in its normal position after said electric lock becomes energized and for then displaying a second indication when said lock lever is moved away from its normal position and also for displaying a third indication by an aspect which is different from the aspect of said indication means for displaying either said first or said second indication when said lock lever is returned to its normal position.

10. In a control and indication arrangement for an electric lock for a lock lever which locks a railway track switch in its normal position and with which a take-siding indicator is associated which directs traffic movements over said switch in the reverse position, the combination comprising, manually controllable means for energizing said electric lock for releasing said lock lever and for closing a contact in a circuit for energizing said take-siding indicator, and indication means controlled for displaying a given indication while said lock lever remains in its normal position after said electric lock becomes energized and for then displaying a second indication when said lock lever is moved away from its normal position and also for displaying a third indication by an aspect which is different from the aspect of said indication means for displaying either said first or said second indication when said lock lever is returned to its normal position.
